UNITED STATES PATENT OFFICE.

ANDREW E. JONES, OF RICHMOND, INDIANA, ASSIGNOR TO ANDREW E. JONES & CO., OF SAME PLACE.

VEHICLE-HEATER.

SPECIFICATION forming part of Letters Patent No. 471,866, dated March 29, 1892.

Application filed November 26, 1890. Serial No. 372,689. (No model.)

To all whom it may concern:

Be it known that I, ANDREW E. JONES, of Richmond, in the county of Wayne and State of Indiana, have invented a new and useful 5 Improvement in Vehicle-Heaters, of which the following is a full, clear, and exact description.

My invention is an improvement in that class of heater attachment for vehicles which 10 are applied to and suspended from the bottom of the latter.

To these ends my invention consists in certain features of construction and combinations of parts, which are hereinafter described, and 15 indicated in the claims.

Reference is to be had to the accompanying drawings, forming a part of this specification, in which similar letters of reference indicate corresponding parts in all the figures.

20 Figure 1 is a front elevation, partly in section, of a vehicle-body and a dash-board, broken, showing the heating devices in position thereon, one heater being in vertical section taken on the line 1 1 in Fig. 2. Fig. 2 is

25 a plan view of a vehicle-body front portion, broken, a dash-board thereon, and two similar heating devices in connection with a heat-distributer and a register, also shown, the draft-flue of the smoke-chamber being represented broken, and the top of one heater.

30 Fig. 3 is a longitudinal elevation in section of one heater, the attachments therefor, and a vehicle-body, broken, taken on the line 3 3 in Fig. 1, viewed in the direction of an arrow;

35 and Fig. 4 is an enlarged broken view in section of a portion of the wick-adjusting gear for the heaters.

The heating device, briefly considered, is 40 comprised of a pair of removable shells or heater-casings, which are suspended from the bottom of a vehicle forward of the seat, or, if a two-seated conveyance, in front of the front seat. Lamps are inserted in the casings, which are adapted to throw light in front of

45 the vehicle and also to transfer radiant heat produced by them from the casing to a hollow foot-board and through a register in said foot-board to warm the vehicle occupants, a separate compartment being provided for 50 the reception of the products of combustion

evolved from the lamps and an escape-flue therefrom.

It is intended to employ the improved heater in combination with different styles of wheeled vehicles drawn by horses, and will 55 be described in connection with a front portion of such a conveyance.

Upon the front edge portion of the bottom boards A and sides B of a vehicle-body of an approved form of construction a dash-board 60 C is secured in an erect position. Said dash-board is made of any suitable preferred material, either wood, metal, leather, or a combination of either. Within the vehicle-body at a proper point removed from the dash- 65 board C a composite metal foot-board D is located, it being preferably made of sheet metal of a proper size proportionate to that of the vehicle-body and may be extended to afford a heat-radiator for carriages having 70 two or more seats or be placed in front of a single seat. For illustration the latter form is shown.

The foot-board D consists of three rectangular metallic plates c c' c², that are held 75 spaced apart by the side walls and end walls of the foot-board and properly secured thereto, so as to provide two parallel horizontal compartments, which extend a proper width and are of such a proportionate length that the 80 end walls will be adjacent to the sides B of the vehicle-body.

Near each end of the foot-board D circular apertures are formed, one above the other, in the walls c c' c² of this structure, which orifices at each end are above a concentric circular hole made in the bottom board of the vehicle-body, whereby provision is made for the insertion through the several orifices mentioned of a cylindrical casing E at each side 90 of the body, which casings hang pendent by their radial top rims d, by which they are attached to the lower plate c of the foot-board, whereon they are imposed.

The casings E are of equal dimensions, and 95 each have an air-hole d' cut through their bottom wall, and, as shown in Fig. 1, there is a glazed door e placed over a side aperture cut in the front of each of the casings to provide for access to their interiors from the 100

outside, said doors being mounted in slide-ways for convenience in manipulation when they are to be moved. The vertically-rang-ing apertures in the plates or walls c c' c^2 are 5 guarded by a three-plate cover F for each set of holes, and, as represented at the left side of Fig. 1, said covers each consist of plate metal disks g g' g^2 , having such relative di-ameters to the sizes of the holes they cover 10 that each plate will overlap the edge of the respective aperture which it covers and rest upon the marginal portion of the respective walls c c' c^2 . The upper plates g of the cov-ers F and the intermediate plates g' of the 15 same are spaced apart by studs h , so as to re-tain them separated a proper distance and adapt them to fit upon the orifices they are de-signed to close. A row of circularly-arranged thimbles i , inserted in aligning holes in the 20 intermediate cover-plates g' and the lower cover-plate g^2 , forms a series of communicat-ing passages from the interior of each pendent casing E to the upper compartment G of the foot-board.

25 A suitable lamp H , of any preferred style that is adapted for the service, is provided for each casing E , wherein they are retained re-movably by rigid suspension from the com-pound covers F of the casings they occupy, 30 said pendent connection of each lamp being effected by the hanger-bars k , that are at-tached by their upper ends to the bottom cover-plates g^2 and by their lower ends to the oil-reservoirs of the lamps, as represented in 35 Fig. 1.

Each lamp H has a stout bracket-arm m at-tached to its burner, which arms are bent down wardly and then outwardly to afford a horizontal support m' for a bevel-pinion m^2 40 near each burner air-chamber. Said pinions (shown enlarged in Fig. 4) are revolvably sup-ported in orifices made for their depending hubs m^3 in the support m' and have axial square apertures formed in each for the easy 45 introduction and removal of an upright rod n , that extends vertically and passes through a thimble i and an aligning perforation in the top cover-plate c^2 . Each rod n has a con-venient handle n' on its upper end to facil-50 itate its introduction and removal and also provide means for the revolvable movement of the same when needed. The shafts whereon the wick-adjusting wheels of each burner are placed project sufficiently to receive on the 55 end of each shaft a bevel-pinion m^4 , which is so relatively located as to permit it to mesh with a pinion m^2 , whereby means are afforded for the convenient adjustment of the lamp-wicks when the heater is in service.

60 The lower compartment I of the foot-board D is designed to form a conduit for the prod-ucts of combustion from the lamps H , and to this end their chimneys J are extended up through an opening made in the lower cover-plate c of each compound cover F , so that the 65 evolved heat and gases thrown off from the burners and all odors arising from the burn-

ing of the oil-lamp will enter the lower com-partment I , where the large area afforded will permit the major portion of the heat to be 70 absorbed by the intermediate wall c' , which in turn will transmit it by radiation to the upper compartment G , the smoke passing through the flue K , that extends rearward.

All the radiant heat from the large chim-neys J is thrown off in the casings E and min-gles with air that enters the apertures in the 75 lower walls of the casings, which openings may be made adjustable for size by any pre-fered means in common use. (Not shown.) 80

There are one or more heat-controlling reg-isters M placed near the center of the foot-board D , which by adjustment will graduate the exit of heat-currents from the foot-board to warm the lower extremities of occupants 85 of the vehicle by its direct contact therewith; but it will be evident that the heat within the compartment G will be so diffused therein that contact of the feet of the persons in the vehicle with the top plate c^2 will warm them 90 if the lamps within the casings E are prop-erly regulated by the means provided.

When the lamps are burning, the light emitted will shine through the doors e by rea-son of their transparency, so that ample 95 illumination of the road-bed ahead of the horse or team will be afforded.

As it is desirable that the driver should be enabled to inspect the condition of the lamps H while in service and the vehicle is in mo-tion, provision has been made to effect this, 100 which consists in providing openings in each casing E above the doors e and in the bottom board A in advance of the foot-board D at points above and laterally aligning one with 105 the other, which openings are connected by tubes p , thereby affording diagonal conduits for light from the lamps, which will be re-flected by the mirrors N , secured on the dash-board B adjustably in the guides N' 110 opposite the conduits, which latter also serve to convey heat to the feet of the occupants of the seat adjacent thereto.

The bail-handles r are provided to enable the removal of the lamps H from the casings E , and thus facilitate the replenishing of oil 115 and trimming of the wicks, said bails being hinged to the top plates c^2 of the covers F , so as to lie flat when not in service. Said cas-120 ings E may also be removed by the bails and the lamp therein be utilized as a lantern, if desired.

It is not absolutely required that the cas-125 ings E be hung from the lower wall c of the foot-board D , as other means of support may be provided and as good results follow. Hence I do not wish to restrict the construc-tion of the device to the position of casings, 130 nor do I wish to be confined to the precise means shown for regulating the height of the wicks from the interior of the vehicle, as other well-known means—such as sprocket-wheels and chains therefor, or frictional gearings—may be substituted therefor, the plan of

construction herein shown being preferred as most convenient, reliable, and inexpensive to manufacture.

Having thus described my invention, I claim as new and desire to secure by Letters Patent—

1. A vehicle-heater comprised of a metallic foot-board that has two compartments, one above the other, and two similar heating devices that are pendent near the ends of the foot-board and adapted to transmit their radiant heat into the upper compartment and the products of combustion into the lower compartment, substantially as set forth.
2. The combination, with a hollow metallic foot-board divided into two compartments and a pendent casing adapted to receive a lamp, said foot-board having an opening through its top and bottom walls and its partition aligning with said casing, of a three-

plate cover having thimbles connecting its bottom and intermediate plates and a central aperture in its bottom plate, substantially as set forth.

3. The combination, with a foot-board provided with a heat-escape register and which is comprised of two elongated chambers, one above the other, and having three parallel walls which are coincidentally apertured, and a three-plate cover for the vertical passage in the foot-board, of a casing below the apertures provided with a glazed opening, a lamp hung from the cover and concentric within each casing, and a device to regulate each lamp, substantially as set forth.

ANDREW E. JONES.
